L. R. WEINBERG

DUSTPROOF PIANO COVER

Filed May 23, 1922

Inventor
Laurence R. Weinberg

E. B. Bradford -
Attorney

UNITED STATES PATENT OFFICE.

LAURENCE R. WEINBERG, OF CLEVELAND, OHIO.

DUSTPROOF PIANO COVER.

Application filed May 23, 1922. Serial No. 563,026.

To all whom it may concern:

Be it known that I, LAURENCE R. WEINBERG, a citizen of the United States, residing at Cleveland, in the county of Cuyahoga and State of Ohio, have invented certain new and useful Improvements in Dust-proof Piano Covers, of which the following is a specification.

My said invention relates to a dust proof cover for pianos, which with slight modifications may also be found useful for other articles of furniture such as davenports, dressers and the like.

It is an object of my invention to provide a dust proof cover which may be made up in a single piece and can be quickly applied to or removed from furniture.

A further object of the invention is to provide a cover which shall securely enclose every part of the object protected thereby and which shall thoroughly safe-guard the same against entrance of dust at any point.

Referring to the accompanying drawings which are made a part hereof and on which similar reference characters indicate similar parts,

Figure 1 is a plan of the cover in open position prior to the sewing together of part of the edges, and

Figure 2, a perspective of a piano with a cover applied thereto.

In the drawings reference character 10 indicates the bottom of the cover which is next to the floor in applied position, 11 indicates the front, 12 the top, and 13 the top back which hangs over the piano at the rear side. The back is indicated at 14, the top back and back proper being shown in Figure 2 as partly rolled back to indicate the connections for the edges of the different sections. The side sections are indicated at 15 and extending therefrom are the back flaps 16. Straps 17 are secured to the back flaps and straps 18 to the back and top back sections respectively.

The bottom section has openings 19 for the front casters and 20 for the rear casters, the openings 20 being oblong to permit application of the cover to any of the well known pianos some of which have the rear casters differently set from others. At the edges of the top back section and at corresponding parts of the back flaps there are rows of snaps 21.

Before putting my device in use I prefer to sew the edges of the blank shown in Fig-

ure 1 beginning at 22 on the top back, i. e., about two inches from the top of the piano, and sewing together the corresponding edges of the top back, top, front and bottom to the corresponding edges of the side flap and rear flap as indicated in Figure 2 by dotted lines 23. The back and the greater portion of the top back remain unattached as well as the back flaps.

In the use of my device the bottom part is located underneath the piano with the casters projecting through openings 19 and 20 and the cover as a whole forms a sort of a bag which can readily be brought over the piano from the front. The back flaps are now strapped together by straps 17, the back and top back are secured together by straps 18 and the top back is secured to the back flaps by snaps 21. In this way it will be seen that all the top, front and bottom edges of the piano are enclosed by either integral or sewed edge portions of the cover while the rear portion of the piano is similarly enclosed or else is enclosed by parts which overlap to a considerable extent thus effectively excluding dust from the instrument.

It will be obvious to those skilled in the art that the device may be modified in various respects to serve as a cover for pianos or other articles of furniture all without departing from the spirit of my invention, the true scope of which is indicated in the appended claims.

Having thus fully described my said invention what I claim as new and desire to secure by Letters Patent, is:

1. A one piece dust proof piano cover comprising a front section, a top section adjacent the front section and a top back section adjacent the top section, a bottom section adjacent the front section and extending opposite to the aforesaid sections, a back section adjacent the bottom section, a pair of side sections similarly shaped adjacent opposite sides of the front section, a back flap adjacent each side section, said parts being so formed that when applied to the piano all the top, front and bottom edges of the piano are enclosed, the top back section overlapping the back section, and the back section overlapping the back flaps, substantially as set forth.

2. A one piece dust proof piano cover comprising a front section, a top section adjacent the front section and a top back sec-

- tion adjacent the top section, a bottom section adjacent the front section and extending opposite to the aforesaid sections, a back section adjacent the bottom section, a pair of 5 side sections similarly shaped adjacent opposite sides of the front section, a back flap adjacent each side section, said parts being so formed that when applied to the piano all the top, front and bottom edges of the piano 10 are enclosed, the top back section overlapping the back section, and the back section overlapping the back flaps said overlapping straps having cooperating straps for holding the sections in place, substantially as set 15 forth.
3. A one-piece dust proof piano cover comprising a body section, top and bottom sections adjacent the body section and extending in opposite directions therefrom, 20 said top section having an extension adapted

to overlap the opposite side of a piano from the body section, said bottom section having an extension adapted to also overlap the opposite side of a piano, a pair of similarly shaped end sections adjacent opposite edges 25 of the body section, each of said end sections having extensions forming flaps, the arrangement being such that when applied to a piano the extensions on the top and bottom sections overlap the flaps on the end sections to inclose all the edges of the piano, substantially as set forth.

In witness whereof, I have hereunto set my hand and seal at Cleveland, Ohio, this 17th day of May, A. D., nineteen hundred 30 and twenty-two.

LAURENCE R. WEINBERG. [L. S.]
